PLUNGER CONTROLLED VALVE FOR OIL
WELL PUMPS

William J. Dunlap, Long Beach, Calif.

Application September 14, 1938, Serial No. 229,919

2 Claims. (Cl. 103—180)

This invention relates to improvements in well pumps and is primarily designed to be employed in well pumps used in oil wells.

An object of the present invention is to provide an improved well pump wherein the valves of the pump are prevented from spinning. Considerable difficulty has been encountered in many types of oil pumps with respect to damage done to the valves of the pump and their adjacent cages. Where ball type valves are used, valves sometimes wear out of round causing leakage. One of the greatest difficulties experienced, however, is that cages for the valves become badly damaged. The damage done to the cages is frequently found to be on the upright arms of the cage rather than the top thereof as might be expected, and this damage done to the cages and to the valves themselves is largely due to the action of the liquid being pumped at the extreme pressures causing the valves to open and to be thrown violently against the sides of the cages. Difficulty has also been experienced in oil well pumps due to what is commonly called gas locking.

It is an object of the present invention to provide a well pump wherein provision is made to prevent the valves from spinning or from being thrown violently against the sides of the cages and which provides a mechanical construction that will frequently urge the valves into open and closed positions, thus eliminating any tendency of the pump to become gas locked.

Another object of the invention is to provide a well pump wherein provision is made for locking the movable or working barrel against rotation relative to the stationary part of the pump so that in the event that the sucker rod loosens or unscrews, as frequently occurs, the working barrel may be locked against rotation to enable the tightening up of the loosened sucker rod.

With the foregoing and other objects in view, which will be made manifest in the following detailed description and specifically pointed out in the appended claims, reference is had to the accompanying drawings for an illustrative embodiment of the invention, wherein:

Figure 1 is a partial view in vertical section through a well tubing illustrating the major portion of the pump embodying the present invention as disposed therein;

Fig. 2 is a partial view in vertical section illustrating the working parts of the pump embodying the present invention, the pump in this view being shown on its upward stroke;

Figs. 3, 4, 5, and 6 are horizontal sections taken

substantially upon the lines 3—3, 4—4, 5—5, and 6—6, respectively, in the direction indicated;

Fig. 7 is a view similar to Fig. 2 illustrating the pump on its downward stroke;

Fig. 8 is a partial view in vertical section illustrating the spring lock on the pump, engaging the shoe on the tubing and showing the manner in which the plunger or working barrel is locked against rotation to enable tightening up of the sucker rod; and

Figs. 9 and 10 are views illustrating alternative forms of valves that may be employed.

Referring to the accompanying drawings wherein similar reference characters designate similar parts throughout, the well tubing is indicated at T having a shoe S, see Figs. 1 and 8, and within which there is disposed a sucker rod R.

The pump comprises a spring lock 10, the fingers of which are adapted to enter and to snap into a seat 11 in the shoe S. Attached to the spring lock is an inner tube 12 which extends upwardly therefrom and has mounted thereon a stationary or inner barrel 13. The stationary or inner barrel is made up of a plurality of sections connected by internal collars 14, 15, and 16. Over the internal barrel there is telescopically mounted an outer or working barrel 17 having at its top a cage 18 provided with a threaded pin 19 for connection to the sucker rod R. The cage 18 is ported as indicated at 20 and serves to cage a traveling or working valve 21 which seats on a seat 22 mounted in the working barrel 17. The traveling valve 21 carries a guide pin 23 which extends upwardly into a bore 24 in the top of the cage with a close sliding fit. 25 designates an outlet or vent from the top of this bore. A rod 26 is threaded or otherwise rigidly secured to the traveling valve 21 and extends downwardly therefrom. It slidably extends through the top of a cage 27 for a standing valve 28 which is designed to seat on collar 16 or equivalent valve seat. The rod 26 also slidably extends through the standing valve 28 with a close sliding fit.

While many well pumps are equipped with merely a single standing valve, in view of the fact that it is common practice to employ two standing valves, I have illustrated a second standing 29 adapted to seat on collar 14 or other seat and which is equipped with a cage shown as being provided by the spider of collar 15. Rod 26 slidably extends through the spider and through the lower standing valve 29 with a close sliding fit.

The bottom of the working barrel is equipped with a nut or thimble 30 which closely fits about

tube 12. This nut is equipped with downwardly extending lugs 31 adapted to enter complementary recesses 32 in the top of the spring lock 10.

The operation and advantages of the improved 5 pump are as follows: During the upward stroke, as illustrated in Fig. 2, the traveling valve 21 is seated. The rod 26, however, is drawn upwardly through standing valves 29 and 28 and the cages for these valves. As the rod has a close sliding 10 fit through the standing valves 29 and 28, the friction of the rod urges the standing valves into open position as shown. At the same time, the rod provides a means for preventing the standing valves from spinning or being violently 15 thrown against the sides of their respective cages.

During the downward stroke, as shown in Fig. 7, the rod 26 slidably extends downwardly through the two standing valves and frictionally urges the standing valves to close. As the 20 rod is guided by the guide pin 24 and rod 26 extending through the cages, the traveling valve 21 is likewise prevented from spinning or being 25 violently thrown against the side of its cage. In this way, the valves are effectively guided and a mechanical connection is formed between the 30 plunger or working barrel and the standing valves to frictionally urge the standing valves into open and closed positions on upward and downward strokes of the working barrel.

In the event that the sucker rod R loosens or becomes unscrewed, as not infrequently occurs, the sucker rod R may be lowered until the lugs 31 enter the recesses 32. This locks the working 35 barrel against rotation with respect to the spring lock 10. The spring lock 10, which is conventionally employed, is of such construction that it will resist rotation of the spring lock with respect to the shoe S; thus by locking the working 40 barrel against rotation with respect to the shoe S on the tubing the sucker rod may be tightened up whenever occasion requires. The working barrel may then be lifted to disengage the lugs 31 from the recesses 32 and pumping continued.

Whenever it is desired to pull the pump, the nut 30 engages a nut 33 at the top of the tube or pipe 12 and by imposing a tension on the sucker

rod R the spring fingers of the spring lock may be contracted and withdrawn from shoe S.

In Figs. 9 and 10 I have illustrated alternative forms of valves which may be employed in place of the type of valves illustrated in Figs. 2 and 7. 5 Fig. 9 shows an elongated traveling valve 21a having a stem 23a and a rod 26a which slidably extends through the cages for the valves 28a and 29a and also through the bodies of these valves. In operation, this form of construction is the 10 same as that previously described.

In Fig. 10 the use of the ball type valves is disclosed wherein the traveling valve is indicated at 21b having the guide stem 23b and the rod 26b slidably extending through the standing 15 valves 28b and 29b.

From the above-described construction it will be appreciated that the improved oil pump effectively prevents spinning of the valves or their being thrown violently against the sides of their 20 cages. Furthermore, the standing valves are influenced by the frictional drag of the rod 26 so that they will be urged to open and close in accordance with the direction of stroke of the 25 plunger.

Various changes may be made in the details of construction without departing from the spirit or scope of the invention as defined by the appended claims.

I claim:

1. A well pump comprising an inner barrel adapted to be seated in a well tubing, one or more standing valves mounted within the inner barrel, a plunger telescoped over the inner barrel, a working or traveling valve on the plunger, and means on the plunger engageable with the inner barrel for lifting the inner barrel when the plunger is pulled.

2. A well pump comprising an inner barrel adapted to be seated in a well tubing, one or more 40 standing valves mounted within the inner barrel, a plunger telescoped over the inner barrel, a working or traveling valve on the plunger, means on the plunger engageable with the inner barrel for lifting the inner barrel when the plunger is 45 pulled, and a rod secured to the traveling valve slidably extending through the standing valves.

WILLIAM J. DUNLAP.
